LOUIS J. FARLAND, OF AU SABLE FORKS, NEW YORK.

MEAT-TENDERER.

1,106,642.

Specification of Letters Patent. Patented Aug. 11, 1914.

Application filed July 10, 1913. Serial No. 778,403.

To all whom it may concern:

Be it known that I, LOUIS J. FARLAND, a citizen of the United States, residing at Au Sable Forks, in the county of Essex and State 5 of New York, have invented a new and useful Meat-Tenderer, of which the following is a specification.

This invention relates to improvements in devices used in the process of rendering 10 meats tender, preparatory to the cooking thereof.

The object is to provide a simple device having means for forcing air through the fibers and tissues of the meat to partially 15 separate the same, and thus cause the meat to become more tender and palatable after it has been cooked.

Another object is to provide a device of 20 this character of a strong construction so as to withstand the comparatively heavy hammering or pounding incident to its use in the process of tendering the meat, and also to provide a device that may be readily and 25 thoroughly cleaned after each operation to maintain it in a sanitary condition.

With these and other objects in view, the invention consists in the construction and 30 novel combination of parts hereinafter fully described, illustrated in the accompanying drawing and specifically pointed out in the 35 claims hereto appended; it being understood that various changes in the material, form, size, proportion and minor details of construction may be resorted to without departing 40 from the spirit or sacrificing any of the advantages of the invention.

In the drawing in which like reference characters designate corresponding parts in 45 each of the figures: Figure 1 is a perspective view of the improved meat tenderer. Fig. 2 is a vertical longitudinal sectional view of the same.

The device of the present invention consists of a tubular head 1 formed of a suitable 50 length of metallic tubing, preferably steel, of proper diameter and of sufficient strength and thickness to withstand the rough usage to which the device may be put. This cylindrical head is provided intermediate its ends 55 with a partition 2, which is formed of metal and is securely fastened within the head, as by welding, shrinking or soldering, thereby providing at either end of the head air pockets or chambers 3 and 4 for a purpose to 60 be hereinafter described. The tubular head 5 may, however, be formed integral with the

partition 2 or any desirable means for securing the two together may be employed. The central partition is of sufficient thickness to admit of being counterbored and threaded 60 to receive the inner threaded end 5 of a horizontally disposed rod 6 which is passed through a perforation in the side of the head 1, registering with the bore of the partition 2, and is screwed into or otherwise securely 65 held in engagement with the head 1. The rod 6, which is of the proper length to lend the necessary force to the blows during the process of hammering or pounding the meat to render the same tender, is provided at its 70 outer end with a suitable handle 7 in order that the device may be more easily manipulated. One end of the tubular head 1 is preferably provided with a cutting edge 8, formed by beveling the inner side of the 75 peripheral wall thereof to provide a knife-edge which may be readily resharpened from time to time as may be found necessary. The other end 9 of the said head member is left blunt or of the original thickness 80 of the tubing, for a purpose to be explained.

In the operation of the device, it is only necessary to use the same in the manner of a hammer, that is, by pounding the meat to be made more tender after the same has been 85 placed on a suitable support with either one or the other end of the device, depending on the condition of the meat to be treated. If the meat is already comparatively tender and palatable, it will be necessary to use 90 only the blunt end 9 of the device in hammering or pounding the meat, when the air pocket 4 will act, after the said edge 9 has come into contact with the meat to compress the air contained within said pocket or 95 chamber 4, and force the air into and through the meat, separating the fibers and tissues and thus treating every particle of the meat without wasting any of the juices. If, however, the meat is tough or stringy, it 100 is only necessary to reverse the device and use the sharp edge 8 against the meat, when the pocket 3 will act to compress the air within the same, as the said edge 8 is embedded in the meat, and the air will act in the 105 manner heretofore described. In addition, the cutting edge 8 will aid in tendering the meat by severing the tissues and fibers thereof and causing the same to become tender and toothsome.

It will thus be seen that a simple and efficient device has been provided which is

adapted to perform the work of rendering steaks, chops and other forms of meat more tender, and that the device may be readily cleansed and kept in a clean and sanitary condition with very little labor, and at the same time the said device is of strong and simple construction and adapted to withstand the hard usage to which such devices are subjected.

19 10 What is claimed is:—

1. A meat tenderer, comprising a tubular head, air pockets provided at each end of said head, said pockets having their outer ends open and provided thereat with meat penetrating edges, the pockets being of materially greater depth than the depth of penetration of said edges, whereby the air in the pockets will be compressed when said edges are brought forcibly in contact with meat and an outwardly extending operating handle secured to the said head at an intermediate point thereof.
- 15 2. A meat tenderer, comprising a tubular head having meat penetrating edges at each end, a partition provided within the head and forming air pockets on each side of the

partition having their outer ends open, the pockets being of materially greater depth than the depth of penetration of said edges, whereby the air in the pockets will be compressed when said edges are brought forcibly in contact with meat and a laterally extending operating handle secured to the head and partition.

3. A meat tenderer comprising a tubular head, a partition provided within the head, said partition forming air pockets on each side thereof, one end of the head being blunt and the other formed with a cutting edge, the pockets being of materially greater depth than the depth of penetration of said edge, whereby the air in the pockets will be compressed when said edge is brought forcibly in contact with meat and a handle connected to the head.

In testimony, that I claim the foregoing as my own, I have hereto affixed my signature in the presence of two witnesses.

LOUIS J. FARLAND.
